UNITED STATES PATENT OFFICE.

WARD MELVILLE, OF OLD FIELD, NEW YORK, ASSIGNOR TO MELVILLE SHOE CORPORATION, A CORPORATION OF NEW YORK.

DESIGN FOR A STORE FRONT.

Application filed June 19, 1928. Serial No. 27,199. Term of patent 14 years.

To all whom it may concern:

Be it known that I, WARD MELVILLE, a citizen of the United States, residing at Old Field, Suffolk County, State of New York, have invented a new, original, and ornamental Design for Store Front, of which the following is a specification, reference being had to the accompanying drawing, forming a part hereof.

In the drawings,

Fig. 2 is a section view of the same taken on the lines 2—2 of Figure 1.

I claim:

The ornamental design for a store front, as shown.

WARD MELVILLE.
